UNITED STATES PATENT OFFICE.

GEORGE W. LONGMAN, OF PATERSON, NEW JERSEY.

TAPPING AND DRILLING MACHINE.

SPECIFICATION forming part of Letters Patent No. 259,406, dated June 13, 1882.

Application filed March 24, 1882. (No model.)

To all whom it may concern:

Be it known that I, GEORGE W. LONGMAN, a citizen of the United States, residing at Paterson, Passaic county, State of New Jersey, have invented a new and useful Improvement 5 in Tapping and Drilling Machines, of which the following is a specification, reference being had to the accompanying drawings, forming a part thereof.

10 My invention relates to devices for tapping of holes in boilers, &c., and has for its object the production of a portable device, to be operated either by hand or by power, to drill holes in metal and tap the same perpendicularly, 15 horizontally, or at any desired angle.

Figure 1 is a plan view of my newly-invented tapping and drilling device, showing it horizontally. Fig. 2 is a side view of the same at an angle. Fig. 3 is an end view of 20 the same arranged perpendicularly, and Fig. 4 is a sectional view of my improvement.

a represents a bed-plate, on which are erected two standards, a' a', that support a driving-shaft, d, and an adjustable frame, f, having a sleeve, f', into which sleeve one end of the shaft d is journaled. On the outer end of the shaft d there is arranged a crank, b, to operate the device when the same is worked by hand, or a driving-pulley when operated by power. The inner end of the shaft is provided with a beveled-gear wheel, e, that gears with a like gear-wheel, e', located on a driving-spindle, d', that is journaled in the adjustable frame f. The driving-spindle d' is 30 also provided with a channeled gear-wheel, e', and an adjustable frame, f'', having a sleeve, f', that works in the channel of the wheel e', and is kept in position by a collar, h'. Journaled in one of the forks of the adjustable frame f'' is a channeled gear-wheel, e'', through which and in which there is journaled a grooved tap or drill spindle, d'', having on the end a collar, i, in which there is a socket, l, into which socket there is arranged a chuck, n. The wheels e' 35 and e'' are provided with suitable feathers, k', that work in the groove k of the spindles d' d''. On the end of the drill-spindle d'' there is arranged a pressure attachment having a collar, o, that fits on the spindle d'', that has a set-screw, o', for securing the same to the drill-spindle d''. In the end of the sleeve p that is

secured to the spindle d'' is arranged a screw, r, to create pressure on the drill-spindle d'' when the same is in operation. By this means the drill is kept hard against the metal and 55 caused to complete its work of drilling the hole. The screw has a square head and taper end that may work in a brace behind the screw. The inner end of the screw r may have a center end, as at t, and work in a corresponding center in the end of the spindle d'', and may be operated by a handle or other means, as desired.

Operation: Motion is given to the driving-shaft d at b. The bevel-gear wheel e, that is secured to the end of the shaft d, engages with the gear-wheel e', located on the driving-spindle d', and rotates the same. The beveled-gear wheel e'' on the end of the driving-spindle d' engages with a like gear-wheel, e'', on the 70 drill-spindle d'' and rotates the same. The driving-spindle d' and the drill-spindle d'' may be operated through the sleeves of the gear-wheels e' and e'' while the same are rotating by means of the operating-handles c c'. 75 The feathers k', working in the grooves k, keep the spindles d' d'' fast for rotating purposes. The adjustable frames f f'' rotating in the channels of the wheels e' e'' and standards a' admits of the spindle d'' being presented in a 80 perpendicular, horizontal, and angular position, as shown in Figs. 1, 2, and 3. The handles c c' turn on the spindle d'' and adjustable frame f'', and offer no obstructions to the rotation of the same. The drill or tap in the 85 chuck n may be thrown on an angle by reason of the socket and ball working therein.

When the device is to be operated by power a portable steam-engine may be located on the bed-plate a, and the bed-plate provided with 90 wheels to form the same into a truck for moving the device from place to place, where the same is required.

The driving-spindle d' may be made any suitable length for practical purposes.

The clutch g, working on feathers k' in the shaft d, may be operated by any known clutch shifting device for throwing the drill in and out of gear when the device is to be stopped or started.

When the drill is to be used by power the sleeve p is placed on the spindle d'' and secured

thereon by set-screws o' in the collars o , and the pressure-screw r operated to keep the pressure on the drill when the same is in use. The same may be operated by hand by removing 5 the sleeve p by unscrewing the set-screws o' and screwing on the operating-handle c' , as shown and described in my former application filed November 2, 1881, No. 45,000, and allowed January 27, 1882, and Letters Patent issued 10 February 21, 1882, No. 254,031. The present application is to secure the pressure attachment to the drill, which is the peculiar feature of my invention.

Having described my improved drill and its mode of operation, what I claim, and desire 15 to secure by Letters Patent, is—

The combination of the drill-spindle d^2 , collars o , set-screws o' , sleeve p , screw r , and head t , substantially as described, and for the purpose shown and set forth.

GEORGE W. LONGMAN.
